CLAIM

The ornamental design for a ski tow for boats, as shown and described.

DESCRIPTION

FIG. 1 is a perspective view of the tow of my new design. FIG. 2 is a top plan view of the tow of FIG. 1. FIG. 3 is a bottom plan view of the tow of FIG. 1. FIG. 4 is a right side elevation view of the tow of FIG. 1. FIG. 5 is a left side elevation view of the tow of FIG. 1. FIG. 6 is a back end view of the tow of FIG. 1; and, FIG. 7 is a front end view of the tow of FIG. 1. In the drawings, the broken lines depict portions of the article that form no part of the claimed design.
